UNITED STATES PATENT OFFICE.

OSWALD GÜLDNER, OF NOSSEN, SAXONY, GERMANY.

HOT-AIR ROTARY MOTOR.

SPECIFICATION forming part of Letters Patent No. 249,832, dated November 22, 1881.

Application filed April 25, 1881. (No model.) Patented in Germany December 29, 1880.

To all whom it may concern:

Be it known that I, OSWALD GÜLDNER, of the city of Nossen, Saxony, in the Empire of Germany, have invented a new and useful Improvement in Hot-Air Rotary Motors, of which the following is the specification.

The nature of my invention consists in the arrangement of a hollow wheel or drum divided into a number of chambers, each of which is 10 provided with a suitable piston or plunger acting upon a stationary sector, thereby turning said wheel or drum, which motion is communicated to the driving-shaft. During the revolution of the wheel or drum the chambers in the 15 same, which are filled with a suitable fluid or gas, pass alternately the boiler, fire, or other heating medium and a suitable cooling arrangement, whereby the fluid or gas in said chamber is alternately heated and expanded or 20 cooled and contracted, causing by its expansion the outward motion or propulsion of its plunger or piston, which latter, when the fluid or gas is again cooled and contracted, moves again inward into said chamber either by the 25 atmospheric pressure or by means of suitable springs.

In the accompanying drawings, Figure 1 represents a side view of my motor, partly in section. Fig. 2 is an end view of the same. Figs. 30 3 and 4 are details.

Similar letters represent similar parts.

D is a hollow wheel or drum, divided by the division-plates *d* into a number of chambers, D', (not less than three,) each of which is provided with a suitable piston or plunger, P, passing through the inner ends, *d'*, between suitable flexible packing, *i*, and attached to slides *s*, having one or more projecting teeth, *r*. The plungers *P* are arranged alternately on and 35 40 the other side of the center line of the drum D, and the slides *s* are guided in suitable grooves in the ring R, attached to the inner periphery of the drum P, so as to allow the teeth *r* to project inward. These teeth *r* act upon a stationary sector, S, attached to the supports or frames B B', which latter support the driving-shaft C. The drum D is attached by means of suitable flanges, *h*, to a wheel, A, fastened upon the shaft C. The outer periphery of the wheel or drum 45 50 D is made circular to increase its surface, against which a suitable furnace, K, is fitted, through which, either by the direct application

of its fire or by the action of any suitable medium heated by the fire in said furnace, the contents of said chambers D' will be heated. 55

O is a chamber to contain cold water, and through which the wheel or drum D is made to pass for the purpose of cooling off said chambers and their contents. The chambers D' of the wheel or drum D are filled with a suitable 60 fluid or gas which easily expands by the application of heat, and easily contracts again by the application of a cold medium. When the chamber D' passes the boiler or heating arrangement K the fluid or gas contained therein 65 will expand, forcing thereby the piston or plunger P outward, which action, on account of its teeth *r* being engaged with the teeth on the stationary sector S, causes the drum or wheel D to turn, and consequently the wheel A and 70 shaft C. When the chamber D', in the course of its revolution, passes through the cooling medium contained in the chamber O, said chamber, and consequently the fluid or gas contained therein, will be cooled off and said fluid 75 or gas will contract, when the piston or plunger P will move again into said chamber either by the atmospheric pressure or by means of suitable springs, *w*, arranged for that purpose, as shown in Fig. 3. 80

The plungers *P* are slightly bent to correspond to their relative position during their motion, and may be lined or filled with a suitable non-conducting substance. The plungers *P* are, as before stated, arranged alternately on 85 the one and the other side of the center line of the drum, wheel, or chambers, and are so arranged that the forward end of two of their slides *s* or teeth shall not be more than about one and one-half inch from each other, (see 90 Fig. 3,) whereby the dead center or point where there is no action against the sector S from one of the plungers will be reduced to about one-half of the pitch of the teeth in said sector.

To prevent any accident from the bursting 95 of the chambers, the wheel W upon the shaft C, and from which the motion is transferred, is arranged between two collars, *n* and *m*, keyed fast upon the shaft C. The hub of the wheel W is provided with cavities, (see Fig. 4,) into which conical ends of keys *e e*, passing through the collar *m*, fit, and held in position by means of a suitable spring, *v*. Whenever the resistance is too great these keys *e e* are forced out 100

of the cavities, and the wheel W will stop, while the drum D and shaft C can revolve freely.

Instead of causing the wheel or drum D to revolve, the same may be arranged to remain stationary and substituting a wheel in place of the sector S, which must in that case be firmly attached to the shaft; and, instead of placing the wheel or drum D upright, the same can be placed horizontal and made stationary, and the heating and cooling apparatus attached to the shaft and carried around with the same. At the same time two or more heating and cooling apparatuses arranged alternately may be arranged around the circumference of the wheel D, whereby the effect will be increased.

What I claim as my invention, and desire to secure by Letters Patent, is—

The combination of a hollow wheel or drum, D, attached to the driving-shaft, and divided into chambers D', filled with a suitable fluid or gas, the plungers P, with teeth r, stationary sector S, heating apparatus K, and cooling apparatus O, applied to the periphery of the drum or wheel D, the whole being arranged to operate substantially in the manner and for the purpose set forth and specified.

OSWALD GÜLDNER.
